SPRING FASTENER OR SIMILAR ARTICLE

Sigurd Walter Bengtsson, Bruksgatan 17,
Goteborg, Sweden

Filed Nov. 17, 1972, Ser. No. 307,655

Claims priority, application Sweden May 18, 1972

Term of patent 14 years

Int. Cl. D8—08

U.S. Cl. D8—264

Fig. 1

Fig. 2

Fig. 3

FIG. 1 is a top plan view of the spring fastener or similar article showing my design;

FIG. 2 is a side elevational view thereof, any other side elevational view having a corresponding appearance with due regard given to slot location; and

FIG. 3 is a cross-sectional view thereof taken along line 3—3 of FIG. 2.

I claim:

The ornamental design for a spring fastener or similar article, as shown and described.
